UNITED STATES PATENT OFFICE.

ARTHUR W. HOLWAY, OF LOS ANGELES, CALIFORNIA.

TIMER.

1,357,455.

Specification of Letters Patent.

Patented Nov. 2, 1920.

Application filed February 18, 1919. Serial No. 277,822.

To all whom it may concern:

Be it known that I, ARTHUR W. HOLWAY, a citizen of the United States, residing at Los Angeles, in the county of Los Angeles, 5 State of California, have invented new and useful Improvements in Timers, of which the following is a specification.

This invention relates to such mechanisms as timers and distributors and it has particularly to do with improvements in a certain general type of timer mechanism; the object of the invention being to facilitate replacement of worn parts in a timer of the type described.

10 In the timer mechanism used on the Ford automobile, a relatively stationary shell carries on its interior an insulating ring in which the four timer contacts are carried. Each of these timer contacts has a stud 15 which extends radially outwardly through the insulating ring and through the shell, with a binding post on the outer end of the stud. The interior face of the insulating ring and of the timer contact is traveled 20 over by a rotating roller contact. This inner periphery wears away very fast so that it is necessary to renew the contacts fairly often. In renewing these contacts it is either necessary to take them out of the 25 shell and out of their setting in the insulating ring by forcing them inwardly, and then place a new set of contacts and finish the inner surfaces of the new set down flush and truly circular with the inner periphery 30 of the insulating ring; or it is necessary to renew the entire shell-ring-and-contact assembly. This latter procedure is what is done in a great many cases. This of course causes the waste of a shell every time a renewal 35 is made. The first mentioned method of renewal necessitates a machine operation on the inner periphery of the new contact in order to obtain a true circular surface over which the rotating roller contact may 40 run.

45

I obviate these difficulties by providing an arrangement whereby the contacts and the insulating ring may be easily removed from the shell and then a new insulating ring with 50 contacts properly set therein may be substituted. The insulating ring itself is comparatively inexpensive. The features of my invention will be best understood from the following description in which reference

is had to the accompanying drawings in 55 which—

Figure 1 is a longitudinal section showing my improved timer mechanism; Fig. 2 is a transverse section taken as indicated by line 2—2 on Fig. 1; Fig. 3 is an enlarged detail 60 section taken as indicated by line 3 on Fig. 1; and Fig. 4 is an enlarged detail view taken as indicated by line 4—4 on Fig. 1.

In the drawings the numeral 10 designates the member or machine part which forms the 65 supporting part or base of the timer. This may, in the usual arrangement, be the crank case of an engine. A timer shaft 11 is journaled in member 10 in any suitable manner. And this timer shaft carries on its 70 outer end a rotating arm 12 to the end of which is pivoted at 13 a roller carrying arm 14. Contact roller 15 is carried on the end of arm 14; and this arm 14 has an extension 14^a on the opposite side of pivot 13 to 75 which a spring 16 is connected, the purpose of the spring being to keep the roller 15 out against the inner periphery 17 of the insulating ring 18 and of the timer contacts 19 which are here shown as four in number. 80 It will of course be understood that my invention is not limited to a timer with four contacts; and further that my invention is not limited to the specific mechanism or arrangement which is herein described; the 85 invention applying broadly to any timer of the general character or class herein described. Insulating ring 18 is mounted in the shell 20 by being pressed into the shell to the position shown. Each one of the contacts 19 has a radial stud 21 permanently 90 affixed or connected to the contact and extending radially outwardly through the insulating ring and through the shell and having on its outer end a binding post 22. Suitable insulation is provided at 23 to insulate the studs and binding posts from the shell. Now in the ordinary kind of construction 95 the elements which I have herein described are used in the combination described; but the studs 21 project through apertures 35 in the shell 20; and if it is desired to place new contacts 19 and a new insulating ring in the shell it is necessary to drive the contacts and studs inwardly and remove them 100 from the insulating ring and then remove the insulating ring from the shell. Then it is necessary to put in the new insulating ring 105

and then insert the contacts from the inside. In other words, such a replacement requires the assembly of the contacts on the insulating ring; and when this is done it is then 5 always necessary to put the whole device in a lathe and finish off the inner periphery 17 of the insulating ring and of the contacts, in order to obtain a true and circular surface. If this is not done, the roller 13 will 10 immediately begin to cause uneven wear on the contacts and insulating ring and the timer thus very soon becomes inoperative.

Now I provide the shell 20 with a set of 15 slots 30 leading from the stud holes 35 to the edge of shell 20. These slots provide that the insulating ring and contact assembly may be bodily removed from the shell and a new one placed in the shell by endwise movement and without necessitating 20 the disassembling of the contacts and insulating rings. It is unnecessary that the insulating ring fit the shell any more tightly than an ordinary easy press fit, so that it can be comparatively easily removed endwise. Then, in order to prevent entry of 25 dirt or moisture to the interior of the timer shell, I provide at 31 a band of spring metal, preferably thin spring steel, which may be easily sprung into place in the position 30 shown, covering the slots and holding itself in place by outward expansion against the inner surface of the shell. This band 31 is wide enough to extend from the base member 10 to the insulating ring 18, thus covering 35 all those portions of the slots which are not covered by the insulating ring itself.

It will be noted that the apertures 35 are conical and the insulating washers 23 are correspondingly conical. The width of slots 40 30 is the same as the bottom diameter of the conical hole (see Fig. 4). When the conical washers 23 are in place and held down by nuts 36 it will be seen that they hold the ring 18 and its contacts 19 against lateral 45 placement because the conical washers cannot move out through the slots 30. But when nuts 36 are loosened and the washers raised, then the ring and contacts may be easily removed because the slots are wide enough to 50 pass the studs 21.

Now it will be seen that my invention not only provides for easy substitution and replacement of worn parts, but it will be seen that my improvement may be very easily 55 applied to any standard timer mechanism of the character described. It is only necessary to cut the slots 30 from the edge of the shell down to the holes which pass the studs 21. After this is once done then subsequent replacements of the contacts are easily made without the necessity of throwing away the shell. For replacements, the assembled insulating ring and contacts are provided, and these of course have the 60 proper circular and true inner periphery. 65

The assembled ring and contacts may be easily placed in the shell without at all disturbing the proper surface alinement of the ring and contact. Thus my invention saves the waste of the shell 20, or it saves the necessity of a machining operation; and in any case it infallibly provides a proper, true peripheral surface for the contact roller to run upon. 70

In making the assembled ring and contacts, for replacement, or for original purposes, the ring may be made of any suitable insulating material and I may preferably use a material that may be cast, formed or pressed into true shape, with the contacts 80 therein, at a single operation. For instance, I may use suitable paper pulp or similar material, and I may press this material into true shape and set the contacts in it at the same time by the pressing operation; thus 85 obviating any subsequent machine work, the article as formed being in a finished state. The same will be true of any suitable material which may be cast or otherwise formed. The contacts are better held in place in such 90 a construction because they and their studs (which are screw threaded) are gripped by the formed material. 95

Having described a preferred form of my invention, I claim:

1. A device of the character described which comprises a shell, an insulating ring fitted in the shell and a plurality of contacts fitted into said insulating ring and having studs connected therewith which extend radially outwardly through the shell, the shell having one end open; characterized by the shell having longitudinal slots extending from said studs to its edge at its open end so that the assembled insulating ring and contacts with their studs may be removed bodily from the shell by endwise movement. 100

2. A device of the character described which comprises a shell, an insulating ring fitted in the shell and a plurality of contacts fitted into said insulating ring and having studs connected therewith which extend radially outwardly through the shell, the shell having one end open; characterized by the shell having longitudinal slots extending from said studs to its edge at its open end so that the assembled insulating ring and contacts with their studs may be removed bodily from the shell by endwise movement; and a ring for excluding dust and other foreign matter embodying a strip of thin spring metal placed inside the edge portion of the shell and of a width equal to the distance between the edge of the shell and the adjacent edge of the insulating ring. 110

3. A device of the character described which comprises a shell, an insulating ring fitted in the shell and a plurality of contacts fitted into said insulating ring and having studs connected therewith which extend ra- 115 120 125 130

dially outwardly through the shell, the shell having one end open; characterized by the shell having longitudinal slots extending from the stud holes in the shell to the edge 5 of the shell so that the assembled insulating ring and contacts with their studs may be removed bodily from the shell by endwise movement, the slots being not as wide as the stud holes, a washer around each stud fitting 10 the stud hole and a nut on the stud holding the washer in place, the washer being larger than the slot width and the stud smaller than the same, so that when the washer is removed the stud may be passed through the 15 slot; and a ring for excluding dust and other foreign matter embodying a strip of thin spring metal placed inside the edge portion of the shell and of a width equal to the distance between the edge of the shell 20 and the adjacent edge of the insulating ring.

4. A device of the character described which comprises a shell, an insulating ring fitted in the shell and a plurality of contacts

fitted into said insulating ring and having studs connected therewith which extend radially outwardly through the shell, the shell having one end open; characterized by the shell having longitudinal slots extending from the stud holes in the shell to the edge 25 of the shell so that the assembled insulating ring and contacts with their studs may be removed bodily from the shell by endwise movement, the slots being not as wide as the stud holes, a washer around each stud fitting 30 the stud hole and a nut on the stud holding the washer in place, the washer being larger than the slot width and the stud smaller than the same, so that when the washer is removed the stud may be passed through the slot.

In witness that I claim the foregoing I 40 have hereunto subscribed my name this 8th day of February, 1919.

ARTHUR W. HOLWAY.

Witness:

V. BERINGER.
